UNITED STATES PATENT OFFICE.

WILLIAM D. MCNAULL, OF TOLEDO, OHIO.

STEAM-BOILER.

SPECIFICATION forming part of Letters Patent No. 687,255, dated November 26, 1901.

Application filed February 6, 1901. Serial No. 46,241. (No model.)

To all whom it may concern:

Be it known that I, WILLIAM D. MCNAULL, residing at Toledo, in the county of Lucas and State of Ohio, have invented certain new and 5 useful Improvements in Steam-Boilers, of which the following is a specification, reference being had therein to the accompanying drawings.

This invention relates to steam-boilers of 10 the kind known as "vertical water-tube" boilers.

The objects of the invention are to produce a steam-boiler of the character named in which the top and bottom drums shall be secured by 15 a strong tube passing through both drums and secured to the outer and inner drum-heads, as well as by the tubes which connect the drums or headers of the boiler; also, to arrange the tubes with special relation to convenience of cleaning; also, to provide for the 20 circulation of water in the boiler by an arrangement of the tubes such as will be explained.

Figure 1 is a vertical longitudinal section 25 of the boiler, showing also the furnace and setting, not herein claimed. Fig. 2 is a cross-section of the boiler above the lower drum and below the upper drum, showing broken parts of the setting. Fig. 3 is a cross-sectional detail of upper T.

The letter A indicates the boiler-casing, and B the furnace, which are of any proper construction to inclose the shell and direct the heat from the furnace between the water-tubes at one side of the boiler, thence upward toward the upper drum, and thence downward toward the uptake or chimney, as at C. The deflector is indicated in dotted lines at D, Fig. 1.

40 The numeral 1 indicates the lower drum. This is of suitable construction, being preferably a short cylinder with one arched and one flat end, the arched end being placed downward and provided with a suitable blow-off 2.

The upper drum 10 is in general the same form as the lower drum, but may be either longer or shorter than the lower drum and has the arched end uppermost. A strong 45 tube 4 extends from the lower head or end of drum 1 up into and through the drum 10. This tube 4 may approximate one-half or one-

fourth of the diameter of the drums. Preferably tube 4 passes entirely through the upper drum 10, and both heads of this drum, 55 as well as both heads of the lower drum, are firmly secured to this tube 4. At the bottom of tube 4 stays 5 are shown, which are riveted to the drumhead and tube and permit circulation of water between tube 4 and drum 1. 60 At the upper end tube 4 has openings 6' to permit circulation to drum 10. The water-tubes 6 6 connect the two flat faces of the drums 1 and 10 and are expanded into holes in these flat heads in usual manner. Man-hole-plates, as 11, in the upper drum permit the entrance of these tubes 6 through the upper drum when necessary to replace a tube. Within tube 4 there is a vertical tube 8 of considerably less diameter than tube 4, but preferably larger than tubes 6. The tube 8 is connected to elbows or T's 9, which extend through the walls of tube 4 and open into the upper and lower drums. The feed-pipe 12 enters the lower drum and opens into 75 pipe 4. The fire from furnace B enters between the water-tubes 6 and is deflected upward by the wall or deflector D. The heated products of combustion pass over deflector D and down between the tubes 6 on the other 80 side of the deflector, and so to uptake C. The tubes 6 on the side of the boiler toward the furnace are arranged in rows at a right angle to the deflector D. Thus a brush or steam-blower can be passed in from the front of the 85 furnace and made to enter between the passages between all the tubes 6 on that side of the deflector, and so the tubes can be cleaned pretty thoroughly. At the opposite side of the deflector D the tubes 60 are arranged in 90 rows parallel to the deflector, and as the boiler-setting has side openings or doors, of usual construction, for the entrance of a brush the tubes 60 can all be cleaned externally by the use of such a brush. Thus while 95 the flame is not permitted to pass directly through the boiler from front to rear, but is deflected, the tubes are still quite readily accessible for cleaning. When the water enters from the feed-pipe, being naturally colder 100 than the water in the boiler it would remain at the bottom, but is forced up inside tube 4 until it reaches the level of the upper T 9. Then by reason of difference of specific grav-

ity the cooler water flows down pipe 8 and out of the bottom T 9 into the lower drum. The intense heat applied to the surface of tubes 6 and 60 carries the water and steam 5 upward through these tubes and into the upper drum. Should the tube 8 be insufficient for down circulation, the tube 4 then comes into play. Being much larger in diameter than tubes 6 and 60, the tendency is for the 10 less-heated water to pass downward in this tube, and all the tubes 6 and 60 being exposed to intense heat causes an upward circulation of the water therein.

A very important feature of the construction of my boiler is the passage of tube 4 through the top and bottom drums and the securing of the same to the outer heads of these drums. This gives a strength to the structure which exceeds that of any similar 15 boiler with which I am familiar. The tube 4 is a heavy tube, generally built up of boiler-plate, and is of sufficient strength to support a very great longitudinal strain. Consequently the drumheads are strengthened and 20 the drums firmly tied together by this vertical tube 4, to which all the drumheads are firmly attached by rivets or other usual securing means.

What I claim is—

30 1. In a vertical water-tube boiler, the combination of an upper drum having a flat bottom and an arched top, a lower drum having a flat top and arched bottom, a series of water-tubes connecting the flat faces of the two 35 drums, and a single central water-tube secured to the inside of the arched face of the lower drum, passing through and secured to the flat faces of both drums, and extending through and above the arched top of the upper 40 drum to which it is secured, said central tube having openings into both drums, substantially as described.

2. In an upright water-tube boiler as described, an upper and a lower drum and water-tubes connecting the proximate faces of the 45

two, manholes in the upper head of the upper drum, so that tubes may be withdrawn or replaced through said drum by cutting and expansion, and a central water-tube extending through both drums and rigidly secured 50 to the four heads of said drums, substantially as described.

3. In a boiler of the character described, the drums connected by water-tubes, the water-tube connected to the outer heads of the 55 drums and extending through both drums, and an internal tube in said connecting-tube and having connection to both drums, substantially as described.

4. In a boiler as described, the drums and 60 tubes connecting them, and a deflector, the tubes between the deflector and furnace arranged in rows at a right angle to the deflector, the tubes at the back of the deflector arranged in rows across the furnace, substantially as described.

5. In a water-tube boiler, the top and bottom drums, a central tube secured to both drums, and a deflector at each side of and extending from said central tube to the casing, 70 all combined substantially as described.

6. In a steam-boiler as described the lower drum practically below the furnace-grate and having a flat upper face, the upper drum above the same and having a flat lower face, 75 water-tubes connecting the flat faces of these drums, a central water-tube passing through the inner faces and connected to the outer faces of the drums, and deflector-plates at the sides of this central tube and forming therewith a central transverse partition extending from the lower drum well toward the upper drum, all combined substantially as described.

In testimony whereof I affix my signature 85 in presence of two witnesses.

WILLIAM D. MCNAULL.
